Charles F. Mowll
Inventor

C. Mowll & Co.

UNITED STATES PATENT OFFICE.

CHARLES F. MOWLL, OF EAST CAMBRIDGE, MASSACHUSETTS.

CAR-COUPING.

SPECIFICATION forming part of Letters Patent No. 449,559, dated March 31, 1891.

Application filed January 16, 1891. Serial No. 378,009. (No model.)

To all whom it may concern:

Be it known that I, CHARLES F. MOWLL, a citizen of the United States, residing at East Cambridge, in the county of Middlesex and 5 State of Massachusetts, have invented a new and useful Car-Coupling, of which the following is a specification.

This invention relates to car-couplings; and the object of the same is to effect certain improvements in draw-heads having open sides.

To this end the invention consists of a draw-head constructed as hereinafter more fully described and claimed, and as illustrated on the sheet of drawings, wherein—

15 Figure 1 is a perspective view of my improved draw-head. Fig. 2 is a central vertical longitudinal section thereof with a link in place.

In draw-heads of this character it very often 20 happens that it is sought to couple the cars after the draw-heads have been brought together either while the cars are at rest or while they are moving. The link is retained in one draw-head by the pin and hangs out 25 of the opening in one side of the draw-head.

The brakeman raises the pin in the other draw-head, throws the link around its pin and into the slot beneath the raised pin, and then drops the latter; but experience has proven

30 that it very often happens, when the coupling is to be done, that there is considerable haste, owing to the fact that the cars are moving or are about to be moved. In such cases it often happens that the brakeman throws the

35 free end of the link with such force that it passes under the raised pin and out the other side of the draw-head, which, being out of his sight, is unobserved. Hence when he drops the pin and hurries out from between the

40 cars he thinks they are coupled, but they are not. It is to overcome this well-known objection to the use of open-sided draw-heads, which are otherwise highly effective and useful, that I have made the present invention.

45 Referring to the said drawings, the letter B designates the draw-bar, and D the draw-head, the latter having the usual vertical hole for the pin P. Transversely through this draw-head is cut an opening O, which is

as deep at the sides of the draw-head as it is at 50 its center directly in rear of the pin, and preferably having a vertically-flaring mouth M.

Coming now to the present invention, the letter R designates a recess cut in the bottom of the opening and of the same size as or a 55 little larger than the exterior of a link L.

The operation is practically the same as above described; but the addition of the recess R serves two important functions, viz: If the link be hanging on the pin shown in Fig. 1 60 and extending out through one side of the draw-head, when this link is thrown around toward the front or into alignment with the draw-bar it will be obvious that the sides of the link will strike the edges of the recess 65 and drop thereinto; or if the link be hanging on the pin in a draw-head (not shown) and its free end be swung around into the draw-head here illustrated it will be obvious that

this free end, when it reaches a correct position, will drop into the recess R, where it belongs, and when the pin afterward descends it will pass directly through the link, as is 70 desired. This recess can be formed in the draw-head when it is cast or forged and will 75 detract from rather than add to the cost of manufacture.

I do not desire to be limited to the precise details of construction, nor to the use of any particular materials, the principal feature of 80 my invention being the recess R.

What is claimed as new is—

In a car-coupling, the combination, with a draw-head having a vertical pin-opening, a transverse opening entirely through the draw-head intersecting said pin-opening, and a recess in the bottom of said opening, of a pin passing vertically through said pin-opening and a link of a size to fit in said recess and to project beyond the end of the draw-head as and 90 for the purpose hereinbefore set forth.

In testimony that I claim the foregoing as my own I have hereto affixed my signature in presence of two witnesses.

CHARLES F. MOWLL.
